UNITED STATES PATENT OFFICE.

JOHN D. MOSER, OF HAMILTON, ONTARIO, CANADA.

DESIGN FOR A CLAMP FOR HOLDING PARTITIONS, &c., IN SHOWCASES AND THE LIKE.

59,670.

Specification for Design.

Patented Nov. 15, 1921.

Application filed February 11, 1921. Serial No. 444,304. Term of patent 3½ years.

To all whom it may concern:

Be it known that I, JOHN D. MOSER, a citizen of the United States, residing at Hamilton, in the county of Wentworth and Province of Ontario, Canada, have invented a new, original, and ornamental Design for a Clamp for Holding Partitions, &c., in Showcases and the like, of which the following is a specification, reference being had to the accompanying drawing, forming part thereof.

Figure 1 is a plan view of the clamp;
Fig. 2 is a side elevation; and,
Fig. 3 is an end elevation.

I claim:

The ornamental design for a clamp for holding partitions, &c., in showcases and the like, as shown.

JOHN D. MOSER.

Witness:

H. G. HENDRY.
